DISPENSER FOR MEASURED AMOUNTS
OF FLUIDEdward J. Joffe, Summit, N.J., assignor to Park Plastics
Co., Inc., Linden, N.J., a corporation of New Jersey

Filed Dec. 4, 1958, Ser. No. 778,129

4 Claims. (Cl. 222—442)

This invention relates to a dispenser, and more particularly to a dispenser of the type that may be made an integral portion of a container, such as a can. More particularly, my invention relates to a dispenser that when attached to a container, will dispense predetermined amounts of fluid each time the container is inverted.

As a particular feature of my invention, I form a dispenser unit that is readily adapted to be inserted into a container to form an integral part of the container. More particularly, the dispenser unit is preferably formed as an integral part with no moving elements such as valves or the like and preferably from some standard plastic material, thereby facilitating its assembly in a container.

As a further particular feature of the invention, the dispenser unit is formed so that it accepts the cap of the container for closing the container, preferably through the forming of screw threads on the dispenser unit.

As a further feature of my invention, the dispenser unit is adapted to dispense a predetermined amount of fluid each time the container in which it is attached is completely inverted, this inversion being effective to prepare the dispensing unit for a subsequent operation thereof, as when the container is righted and then inverted once again. As a particular feature of this part of the invention, the dispensing and the refilling operation or recycling operation will take place regardless of the direction or path of inversion of the container. In other words, the container need not be inverted in a particular direction or in a particular plane.

As a still further feature of my invention, the dispenser unit is so constructed that there can be continuous flow of fluid should the container and the fluid be placed in a particular position.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention. It is important, therefore, that the claims be regarded as including such equivalent constructions as do not depart from the spirit and scope of my invention, in order to prevent the appropriation of my invention by those skilled in the art.

Referring now to the drawings:

Fig. 1 is an illustration showing a container to which my dispenser has been applied;

Fig. 2 is a section taken along lines 2—2 of Fig. 1;

Fig. 3 is a section taken along lines 3—3 of Fig. 2;

Fig. 4 is a section taken along lines 4—4 of Fig. 3;

Fig. 5 is a perspective view of the dispenser unit of my invention illustrating its construction;

Fig. 6 illustrates the container as it is filled and prior to the application of the bottom thereon;

2

Fig. 7 is a view showing the container after it has been righted from its position of Fig. 6;

Fig. 8 shows the container of Fig. 7 inverted with the cap removed for the dispensing of the fluid therefrom; and

Fig. 9 shows the position the container must assume in order to allow continuous flow of the fluid therefrom.

Referring now again to the drawings, and especially Figs. 2—5, but particularly Fig. 5, the dispenser unit of my invention is formed with a cylindrical measuring and dispensing chamber 10 having a closed bottom 11 and an upper end 12. The cylindrical wall defining the lower part of the chamber is designated by reference numeral 13, while the upper end of the cylindrical wall is designated by the reference numeral 14. Screw threads 15 are formed on the upper cylindrical wall 14 for coaction with a closing cap 16 shown in Figs. 1 and 6.

Near midway between the closed end 11 and the upper open end 12 of the cylindrical wall 13, 14, of chamber 10, there is formed a control passage or slot designated generally by reference numeral 20, having the shape of an inverted T when it occupies the position of Figs. 3 and 5. The function of this control passage will be explained shortly. Just below the control passage or slot 20 there is formed integrally with the cylindrical wall 13, 14 a plate 21 having vertical walls 22 and 23 at two edges thereof. Upstanding from the plate 21 is an abutment 24 in which is formed a venting passage 25, the venting passage extending also through the plate 21. This is best illustrated in Fig. 3.

In the preferred type of assembly for which my dispenser is best adapted, portions of the container coact with the walls 22 and 23, as well as the plate 21, to form passages and separating walls as will be apparent. This makes it possible to utilize my dispenser unit without any additional parts and without any difficult operation on the container itself. Thus, the container for which my invention is best adapted is formed as well shown in Figs. 1—3, with a body 30, preferably made of some thin sheet metal. The upper end of the container is bent inwardly at 31 with a shoulder at 32 and then has a further small vertical cylindrical portion 33. This further vertical cylindrical portion 33 is turned inwardly at 34 to enter a groove 35 in the upper wall 14 of the dispenser unit whereby to hold the dispenser unit completely assembled to the container. The dimensions of the part 31 and the shoulder 32 are such that the plate 21 will fit against the shoulder 32 to close off that part of the container below the plate 21 from that part of the container above the plate 21 except at passages to be set forth below.

Thus, there will be narrow passages 40 and 41 as best seen in Fig. 4, between the walls 22 and 23 and the cylindrical container wall 33. Further, there will be communication through the vent passage 25 between the lower part of the container and that portion of the container above the plate 21. In describing my invention, I shall use the letter "C" to define that portion of the container below the plate 21 in Fig. 3, using the letter "R" to indicate that portion of the container defined by the cylindrical wall 33 and above plate 21. Letter R is chosen because this part of the container functions as a reservoir, as will be made apparent shortly.

I shall now describe the operation of the dispenser unit of my invention outlining the filling thereof, together with one dispensing cycle.

As has been indicated, the dispenser unit is assembled within a container so as to form an upper reservoir R generally separated from the remainder of the container C, with communication established between container C

and reservoir R through passages 40 and 41, as well as the vent passage 25. To fill the container, the cap 16 is applied to the screw threads 15 and the container 30 placed in the position of Fig. 6. Fluid is now poured into the container and enters the reservoir R through the passages 40 and 41 until stopped. The bottom is then fixed to container 30.

No fluid will flow above line H in Fig. 6 into that portion of the reservoir designated by reference numeral 50 because of the control exercised by the vent passage 25, it being obvious that once the bottom of the vent passage at line H is closed, no further movement of fluid from the container C is possible. No fluid will flow through the T slot 20 into chamber 10 because of the air trapped in the dispensing chamber 10.

Fig. 7 illustrates the container of Fig. 6 when it has been righted. Upon the righting of the container, the fluid will flow from the reservoir R through the T slot 20 into the lower part of the dispensing chamber 10, the T slot forming a vent until the level of fluid in Fig. 7 is reached. Any excess of fluid will flow through the vent 25 back into the container C, it being obvious, of course, that some fluid will remain about the outer wall of the cylindrical dispensing chamber 10 and between it and the two vertical walls 22, 23, this being the space 50 alluded to in connection with Fig. 6.

The container of Fig. 7 is now ready for a dispensing operation when that is desired. To dispense, the cap 16 is removed and the dispenser is inverted to the position shown in Fig. 8. All of the fluid within the chamber 10 will now flow outwardly in the direction of the arrow 55. Simultaneously, fluid will flow from container C through the passages 40, 41, into reservoir R, as shown by arrow F, with venting taking place at vent 25. The position of the vent 25 is such that the upper surface of the fluid flowing into reservoir R cannot reach above line H in Fig. 8, this being below the lower horizontal opening of the T slot 20. Therefore, no fluid can flow through the horizontal opening of T slot 20 into chamber 10. The vertical portion of control T slot is too narrow for fluid to flow under the circumstances indicated, since there is no venting to permit this flow. Therefore, the fluid will simply fill the reservoir R to the level H and no further fluid will move outwardly of the container C. It will be noted that actually, the amount of fluid within the reservoir R is exactly the same as that in Fig. 6. Now, when the container is righted to the position of Fig. 7, the dispensing chamber is filled as illustrated in that figure with the excess fluid flowing into the container chamber C and some fluid remaining at 50. It is now possible to go through a further dispensing cycle.

In Fig. 9, the container is shown at an angle, and at this angle, the vent 25 will not function to maintain the level of fluid below the horizontal portion of the T slot 20. Therefore, fluid will flow from the reservoir R into the T slot and outwardly through the open end 12 of the dispenser unit. In other words, a continuous flow of fluid is possible when the container is in the position of Fig. 9.

I believe that the operation and novelty of my invention will now be apparent to those skilled in the art.

I now claim:

1. In a dispenser of the class described, a container having a main body for containing fluid, means forming a dispensing chamber closed at its bottom end and having an upper open end extending above the main body of said container when said container is righted, means forming a reservoir surrounding a portion of said dispensing chamber and providing communication for the flow of fluid from said main body into said reservoir together with a permanently open passage between said reservoir and said dispensing chamber, means forming a vertical vent passage extending from said reservoir to said main body and having upper and lower ends, and the greater portion of said permanently open passage being within

the vertical distance defined by the said upper and lower ends of said vent passage when said container is vertical, substantially for the purpose described.

2. In a dispenser of the class described, a container 5 having a main body for containing fluid, means forming a dispensing chamber closed at its bottom end and having an upper open end extending above the main body of said container when said container is righted, means forming a reservoir surrounding a portion of said dispensing 10 chamber and providing open communication for the flow of fluid between said main body and said reservoir together with a permanently open passage between said reservoir and said dispensing chamber, said permanently open passage being shaped to form two area portions 15 of which one area portion is large relatively to the other, means forming a vertical vent passage extending from said reservoir to said main body and having upper and lower ends, and the relatively large area portion of said permanently open passage being within the vertical distance 20 defined by the said upper and lower ends of said vent when said container is vertical.

3. In a dispenser of the class described, a container having a main body for containing fluid, means forming a dispensing chamber closed at its bottom end and having an upper open end extending above the main body of 25 said container when said container is righted, means forming a reservoir surrounding a portion of said dispensing chamber and providing open communication for the flow of fluid between said main body and said reservoir together with a permanently open passage between said reservoir and said dispensing chamber, means forming a vertical vent passage extending from said reservoir to said main body to allow fluid to flow from the said main body into said reservoir when said container is inverted, 30 and the main portion of said permanently open passage being above the lower end of the vent passage when said container is inverted whereby fluid will not reach the level of the main portion of said permanently open passage and will therefore not flow into said dispensing 35 chamber when the container is inverted, the righting of said container bringing the main portion of said permanently open passage as well as said dispensing chamber below the level of the fluid in said reservoir whereby said fluid then flows through said passage into said dispensing 40 chamber.

4. In a dispenser of the class described, a container having a main body for containing fluid, means forming a dispensing chamber closed at its bottom end and having an upper open end extending above the main body 45 of said container when said container is righted, means forming a reservoir surrounding a portion of said dispensing chamber and providing communication for the flow of fluid from said main body into said reservoir together with a permanently open T slot passage between 50 said reservoir and said dispensing chamber, the inversion of said container filling said reservoir which thereafter fills said dispensing chamber through said T slot when the container is righted, the vertical portion of the said permanently open T slot passage being small relatively 55 to the horizontal portion, means forming a vertical vent passage having upper and lower ends and extending from said reservoir to said main body to permit filling said reservoir to the level of the lower end of the vertical vent passage when the container is inverted, and the said relatively large horizontal portion of said T slot lying 60 above the lower end of said vent when said container is inverted and said reservoir is being filled whereby fluid will not flow into said dispensing chamber when the container is inverted but will flow into said dispensing chamber when the container is thereafter righted.
